UNITED STATES PATENT OFFICE.

EDWARD W. WEILAND, OF FRESNO, CALIFORNIA.

SPRING-LATCH AND BOLT.

1,315,266.

Specification of Letters Patent. Patented Sept. 9, 1919.

Application filed June 20, 1918. Serial No. 240,902.

To all whom it may concern:

Be it known that I, EDWARD W. WEILAND, a citizen of the United States, residing at Fresno, in the county of Fresno and State 5 of California, have invented new and useful Improvements in Spring-Latches and Bolts, of which the following is a specification.

The present invention relates to improvements in fasteners for windows, doors, and 10 the like, and the object of the invention is to provide a spring catch which can also be used as a locking bolt to securely lock a window or door.

In the accompanying drawing, Figure 1 is 15 a side view of my improved fastener in its locking position on a door or window; Fig. 2 is a horizontal section on the line 2—2 of Fig. 1; Figs. 3, 4, are cross-sections on the lines 3—3, 4—4, looking in the directions 20 of the arrows.

Referring to the drawing, 1 indicates an edge of a door or window, and 2 a jamb therefor. Secured to said edge by screws 3 are flanges 4 of a plate 6 forming the main 25 portion of the casing of the bolt. The central portion of said plate is rounded in form approximating a semi-cylinder. 7 indicates approximately semi-circular end plates secured to the main portion 6 of the 30 casing by lugs 8 extending from said main portion through holes 9 in said semi-circular plates and being swaged or riveted thereagainst.

Through holes in said end plates can slide 35 a bolt 11 which is for the most part cylindrical in form, so that the hole in one of the end plates is circular to conform to the cylindrical form of the bolt at that end. The beveled or operating end of the bolt is 40 formed on opposite sides with extensions 12 which, when the bolt acts as a spring catch, slide in correspondingly shaped extensions 13 of the hole at that end, which is otherwise circular. When the bolt is in its locking 45 position the extensions 12 are outside the extension slots 13, and the bolt can be turned, the hole 10 in the keeper 15 being elongated to permit the bolt to be so turned. These extensions are of such width that, 50 when the bolt is turned from the unlocking position through a quarter turn into its locking position, as shown in dotted lines in Fig. 4, one of the extensions 12 engages the edge 20 of the keeper at the side toward 55 which the door or window would swing when opened, and binds against said edge

and prevents rattling of the door or window. Through said bolt is screwed a screw 14 within a sleeve 16 forming a finger piece and which can slide in a slot in the round 60 portion of the casing, said slot having a longitudinally extending part 17 and a circumferentially extending part 18. The sleeve 16 serves to limit the movement of the screw into the bolt and also to reduce the friction 65 due to the movement of the bolt in the slot. Around the bolt within the casing is a washer 19, and between the washer and a washer 21 pressing against the outer end plate 7 is compressed a spring 22 coiled 70 around the bolt. The inner ends of the extensions 12 normally, or when the device acts as a spring catch, abut against the washer 21 and prevent its outward movement on the bolt. The purpose of the washer 19 is to 75 prevent said spring from moving into a position where parts of it might engage opposite sides of the sleeve 16. A spring 23 coiled around the bolt is also compressed between the sleeve 16 and the inner side of 80 plate 7 of the casing. The spring 22 is stronger than the spring 23, so as to prevent the bolt being pushed outward by the spring 23 to a position, for instance, opposite to the part 18 of the slot; but it will be observed 85 that the spring 22 exerts no positive inward pressure on the bolt, since it presses at its ends on the washers 19 and 21, both of which act as if fixed on the bolt. The spring 22, however, is of such length and strength as 90 to permit the bolt to be positively moved outwardly by hand so that it can be turned into the circumferential portion 18 of the slot, in which portion it is firmly held by the pressure of the spring 22 pressing the 95 sleeve 16 against the side of the slot.

It will be seen that while the spring 23 acts merely as a latch spring, the spring 22 serves as a yielding resistance, preventing the bolt being moved outwardly too 100 far by the spring 23, and also as a return spring, returning the bolt to its normal position after it has been operated by hand.

The bolt is shown as arranged for a door or window swinging outward. It can easily 105 be reversed so as to be capable of being applied to one swinging inward by unscrewing the screw out of the bolt, moving the bolt outward a sufficient distance to allow it to be turned through a half turn, and then 110 again screwing the screw into the bolt. Thus the fastener can be used to secure any

window sash, door, transom or the like, or in any place where a catch is desired, as the side, top or bottom or center of a double window.

5 By reversing the springs, the device no longer acts as a spring catch but is a locking bolt only.

At the rear end of the bolt is a notch 25 to enable the bolt to be turned by a rotatable 10 instrument when too high to be reached by the hand. 24 indicates a finger piece for closing the door or window.

I claim:—

1. In combination with a keeper, a bolt 15 casing, a bolt slidable therein and having a beveled operating end, a spring normally pressing said bolt outwardly, a spring providing a yielding resistance to the movement of the bolt due to the action of the 20 first-named spring, means whereby the bolt may be turned about a longitudinal axis, means for locking the bolt when so turned, and means for normally preventing the bolt from being turned, but permitting it to be 25 turned when moved longitudinally against the second-named spring.

2. In combination with a keeper, a casing having a longitudinally extending slot, a bolt 30 slidable in said casing and rotatable about a longitudinal axis therein and having a beveled locking end, a finger piece connected to the bolt and movable in said slot, said slot

having a lateral extension to receive the finger piece when the bolt is rotated, means for preventing rotation of the bolt in the casing 35 until it has been moved from its normal position toward the laterally extending portion of the slot, a spring around the bolt and pressing it outwardly, and a spring so resisting the outward movement of the bolt 40 that the finger piece is normally out of registry with the lateral extension in the slot.

3. In combination with a keeper, a bolt, a casing therefor having in its front end an aperture through which the bolt can slide, 45 said aperture having a lateral extension, and the bolt having a lateral extension adapted to slide through the extension of the aperture, said bolt extension being adapted when the bolt is turned about its longitudinal axis 50 to press transversely against a side of the keeper, the casing having a longitudinal slot, a finger projecting from the bolt and slidable in said slot, said slot having a lateral extension, and the bolt extension being out 55 of said aperture extension when the finger is adjacent, or opposite to said slot extension, a washer on the bolt adjacent to the front end of the casing, and spring coiled around the bolt between the finger and the rear end of the casing and the washer respectively.

EDWARD W. WEILAND.
